JOHN GROEME BALSILLIE, OF MELBOURNE, VICTORIA, AUSTRALIA.

WIRELESS-TELEGRAPH RECEIVER.

1,093,240.

Specification of Letters Patent. Patented Apr. 14, 1914.

Application filed February 10, 1914. Serial No. 817,762.

To all whom it may concern:

Be it known that I, JOHN GROEME BALSILLIE, a subject of the King of Great Britain and Ireland, residing at 51 Spring street, 5 Melbourne, in the State of Victoria, Commonwealth of Australia, have invented certain new and useful Improvements in Wireless-Telegraph Receivers, of which the following is a specification.

10 My invention relates to wireless telegraph receivers associated with an air wire or absorbing circuit of the looped type.

My invention is usable in either of two forms, the one for receiving in one certain 15 oscillation frequency and the other for receiving in either of two oscillation frequencies or in two oscillation frequencies simultaneously. In the latter form the receiver is used in connection with two-tone transmitters in which the dots are transmitted in one oscillation frequency and the dashes in another distinct oscillation frequency. The 20 circuits differ from each other in that in the one case one leg of the circuit is operatively idle, the values contained in it being however variable by adjustment of a variometer reactance and a variable condenser included in series in it. In the other case both legs of the absorbing circuit are operative and 25 they each include a variometer reactance and a variable condenser. Oscillation circuits in shunt around these variable condensers are inductively coupled to a quantity detector circuit containing a telephone, which latter 30 circuit is tuned to the group frequency and not to the oscillation frequency of the received waves. The shunt oscillation circuits which are so coupled to the detector circuit are connected to the legs of the absorbing 35 circuits around the variable condensers therein, and they each include as well as their respective variable coupling condensers another variable condenser and a variable inductance, which latter forms the primary of 40 the inductive coupling with the detector circuit before mentioned. In each shunt oscillation circuit the coupling condenser and the variable condenser in said circuit are associated together so that they are varied co- 45

50 equally. This is effected most conveniently by using a swinging double sector condenser in which the intermediate movable plate is connected to the upper part of the absorbing circuit and the outer plates to the shunt containing the variable inductance and to the

foot of the absorbing circuit respectively. The reactance variometers used may be variometers of the "Lorenz" type consisting of two coils, one pivotally mounted within the other and adapted to be turned on its axis, said coils being connected in series, whereby when they are in plane with each other the circuit contains minimum reactance, which is variable up to a predetermined maximum by altering their angular 60 relations up to a maximum which is attained when the axes of the coils are located at right angles. But the same purpose may be effected by otherwise constructing these reactance variometers according to any 65 known method, whereby immediate variation in the reactance in the circuit in which they are contained may be secured by the relative movement of one part of the variometer structure to another part thereof. The 70 detector circuit is tuned to oscillate in the group frequency of the received train of waves by varying the condenser which is in parallel with the telephone connected in 75 said circuit.

80 Referring to the annexed drawings: Figure 1 is a diagrammatic view of the essential parts of a receiver circuit according to my invention, adapted for the reception of waves in one certain oscillation frequency. Fig. 2 is a similar diagrammatic view showing the circuits arranged for the reception of messages in either one or other of two different oscillation frequencies, or for the reception of a two-tone message in 85 which the dots are transmitted by means of waves having one certain oscillation frequency and the dashes by waves having a different oscillation frequency. Fig. 3 is a diagrammatic view showing the coupled condenser connections as used in the receiving shunt circuits, in either arrangement Fig. 1 90 or Fig. 2.

95 In Fig. 1 the absorbing circuit A which must necessarily be of the looped type, is shown as a looped air wire of which the leg a is idle and the leg a¹ is connected to the receiver shunt circuit. The leg a contains in series a reactance variometer X and a variable condenser Y.

100 B and B¹ are connections to earth or a suitable capacity. Inasmuch as the earth, in this connection, operates by virtue of its great capacity, I have employed the term "master-capacity" to express this condition. 110

meaning thereby, either the earth or such other capacity as shall be suitable to the purpose in view.

On the operative side a^1 of the circuit A 5 is a variable condenser C. A shunt circuit including a variable condenser D and a variable inductance E is shunted around the variable condenser C. The inductance E is so formed as to operate as the primary of a 10 coupling transformer of which the secondary G is also variable and forms an inductance in a detector circuit which includes in series with said inductance G a detector H and a variable condenser J. The telephone 15 ear piece K is shunted around the variable condenser J.

The condensers C and D in the shunt circuit are constructed preferably in the manner shown in Fig. 3 but may be otherwise 20 mechanically coupled so that they may be moved only together in equal amount. Any movement of one of these condensers, therefore effects the movement of the other one and the shunt circuit is thus maintained in 25 resonance with the circuit A when any adjustment is made. The inductances E and G are in practice made as the primary and secondary circuits of an air core transformer.

In the case of the receiver shown in Fig. 2 a shunt circuit is used on either leg of the absorbing loop, said shunt circuit being connected electrostatically to said legs respectively on either side of the variable condensers C and Y. Above these shunt connections reactance variometers X and Z are inserted 35 in the circuit. The telephone circuit is as in the previous case tuned to the group frequency of the received wave train while the 40 shunt circuits are in resonance with the absorbing loop and therefore oscillate in the oscillation frequency of the received train of waves. The condensers in the shunt circuits are connected together in the same manner 45 as the condensers C and D, Fig. 1, and the inductances E and E¹ are variable and form primaries of an air core transformer of which the secondary G is included in the telephone circuit. This air core transformer is 50 constructed so that either of the primaries E or E¹ may be rendered inactive in relation to the detector circuit when it is required to prevent reception of waves in the certain oscillation frequency to which that circuit 55 containing it is tuned. The telephone in that case is receptive only to signals received through the other shunt circuit, but where both primary inductances E and E¹ are maintained in active relation to the transformer secondary G, the telephone K will 60 respond to waves having the same group frequency but having distinct oscillation frequencies corresponding respectively with the adjustment of the circuits on either leg of the absorbing loop. In the latter case two

tone messages are readily receivable in the telephone, one of the shunt circuits being tuned to the oscillation frequency of one of the wave trains and the other shunt circuit to the oscillation frequency of the other of them. Similarly when listening in, the operator may detect signals passing in either of two oscillation frequencies and if he desire to receive either of those signals he can by dissociating the primary carrying the other 70 of them, concentrate his attention on the required signals which have their own distinct oscillation frequency. The detector used must be a quantity detector, preferably of the known crystal contact form.

It is obvious that the feet B B¹ of the absorbing circuit A which are connected to earth or a suitable capacity may also be connected together. It is not material whether the variometers X and Z be located above or 80 below the oscillation shunts. The connected circuits whether arranged as in Fig. 1 or Fig. 2 oscillate as a whole, that is to say the currents in the oscillation shunts swing rhythmically with the currents in the absorbing 85 circuit, and the variometers X and Z and the inductances E and E¹ and the condensers C and D and W and Y must be adjusted until the respective values on either side of the loop circuit A are balanced so that the oscillation shunts oscillate freely at the rate of 90 oscillation frequency of incoming waves. Facility for tuning out is thus readily secured. The detector circuit is responsive to any oscillation frequency in either shunt 95 through the medium of the inductive coupling, but it swings in its own time period which is determined by the adjustment of the condenser J at a rate which corresponds to the group frequency and not to the oscillation frequency of the received waves.

Not merely is it possible to tune for one particular oscillation frequency, for any particular receiver may be tuned to receive from any particular transmitter working on 1: the two-tone principle and emitting two distinct wave trains of different frequencies pertaining respectively to dots and dashes but having a certain predetermined group frequency. Reading of the message is therefore possible only when the detector circuit is tuned to the predetermined arbitrary group frequency and either side of the absorbing circuit (Fig. 2) is also tuned respectively to the oscillation frequencies pertaining to the dots and dashes constituting the signals.

What I claim as my invention and desire to secure by Letters Patent is:—

1. A wireless telegraph receiver comprising a looped absorbing circuit the legs of which are connected to a master capacity, one of said legs containing a reactance variometer and a variable condenser and the other of said legs containing a variable con-

denser, an oscillation circuit shunted around said last mentioned condenser and containing a variable condenser and an inductance, and a detector circuit inductively coupled to said 5 oscillation shunt and including a telephone receiver, a variable condenser in parallel with said receiver, and a quantity detector in series with said last named condenser.

2. A wireless telegraph receiver comprising 10 a looped absorbing circuit having legs, both of which are connected to a master capacity, one leg including a variometer reactance and a variable condenser, the other leg including a variable condenser and a 15 shunt circuit connected around said condenser, said shunt circuit itself including a variable condenser and a variable inductance which forms the primary of a coupling transformer and by means of which said 20 shunt circuit can be tuned to the oscillation frequency of the received waves, and a detector circuit coöperating with said shunt circuit and including an inductance which forms the secondary of said transformer, a 25 quantity detector, a variable condenser, and a telephone receiver, said last named condenser and said telephone receiver being connected in parallel.

3. In a wireless telegraph receiver, in combination, a looped absorbing circuit having both of its legs connected to the earth, each of said legs including a variable condenser, one of said condensers being connected in parallel with a shunt circuit and the other 35 of said condensers being connected in series with a variometer reactance, said shunt circuit including a variable condenser and a variable inductance connected in series, said inductance forming the primary of a coupling transformer; and a detector circuit coöperating with said shunt circuit and including an inductance which forms the secondary of said transformer, a quantity detector arranged in series with said inductance, and a variable condenser connected in 40 series with said quantity detector, there being a telephone earpiece shunted around said last named condenser.

4. In a wireless telegraph receiver the 45 combination with a looped absorbing circuit having legs, both of which are connected to a master capacity, each of said legs including a variable condenser and at least one of said legs having therein a reactance variometer; of a shunt circuit connected around each of said condensers, each of said shunt

circuits comprising an additional variable condenser in circuit with a variable inductance, which inductance forms the primary of a coupling transformer; together with a 60 detector circuit which includes an inductance common to both of said variable inductances and forming the secondary of a transformer which is adapted to be energized by either of said primaries, said detector circuit also including a quantity detector and a variable condenser in series with said secondary; and a telephone earpiece in parallel with said last named variable condenser. 70

5. A wireless telegraph receiver comprising, in combination, a looped absorbing circuit having two legs both of which are grounded, a variometer reactance in each of said legs, a variable condenser in each leg 75 and arranged in series with the corresponding variometer reactance, a shunt circuit connected around each of said condensers, each of said shunt circuits itself containing a variable condenser arranged in series with 80 a variable inductance, each of said variable inductances forming the primary of an air core transformer; together with a detector circuit comprising an inductance which forms the secondary of said transformer and 85 is arranged to coöperate with either or both of said primaries, means for detecting the existence of waves in said detector circuit, and means for tuning said detector circuit.

6. In a wireless telegraph receiver, a 90 looped absorbing circuit having legs, a shunt oscillation circuit connected with each of said legs and tuned to different oscillation frequencies, a variometer reactance in each leg of said looped circuit and independent 95 of the shunt in that leg, a variable inductance in each of said oscillation shunts, each of said variable inductances forming the primary of an air-core coupling transformer, and a detector circuit containing an inductance, a quantity detector, a variable condenser, and a telephone earpiece, said last 100 named inductance forming the secondary of said transformer and said variable capacity being in parallel with said telephone earpiece. 105

In testimony whereof I affix my signature in presence of two witnesses.
